(57) **CLAIM**

We claim the ornamental design for a hedge trimmer, as shown and described.

DESCRIPTION

FIG. 1 is a front perspective view of a first embodiment of a hedge trimmer.

FIG. 2 is a left-side elevation view of the hedge trimmer shown in FIG. 1.

FIG. 3 is a right-side elevation view of the hedge trimmer shown in FIG. 1.

FIG. 4 is a front elevation view of the hedge trimmer shown in FIG. 1.

FIG. 5 is a rear elevation view of the hedge trimmer shown in FIG. 1.

FIG. 6 is a top plan view of the hedge trimmer shown in FIG. 1.

FIG. 7 is a bottom plan view of the hedge trimmer shown in FIG. 1.

FIG. 8 is a front perspective view of a second embodiment of a hedge trimmer.

FIG. 9 is a left-side elevation view of the hedge trimmer shown in FIG. 8.

FIG. 10 is a right-side elevation view of the hedge trimmer shown in FIG. 8.

FIG. 11 is a front elevation view of the hedge trimmer shown in FIG. 8.

FIG. 12 is a rear elevation view of the hedge trimmer shown in FIG. 8.

FIG. 13 is a top plan view of the hedge trimmer shown in FIG. 8; and,

FIG. 14 is a bottom plan view of the hedge trimmer shown in FIG. 8.

(Continued)

Broken lines in the drawings show portions of the hedge trimmer that form no part of the claimed design. The dot-dot-dash broken lines in the drawings define the bounds of the claim and form no part thereof.

1 Claim, 10 Drawing Sheets
